UNITED STATES PATENT OFFICE.

LAWRENCE A. SUBERS, OF CLEVELAND, OHIO.

FLEXIBLE INTERLOCKING SPRING-TUBE.

1,133,070.

Specification of Letters Patent. Patented Mar. 23, 1915.

Application filed May 12, 1913, Serial No. 767,200. Renewed August 19, 1914. Serial No. 857,807.

To all whom it may concern:

Be it known that I, LAWRENCE A. SUBERS, a citizen of the United States, and resident of Cleveland, in the county of Cuyahoga and State of Ohio, have invented certain new and useful Improvements in Flexible Interlocking Spring-Tube, of which I hereby declare the following to be a full, clear, and exact description, such as will enable others skilled in the art to which it appertains to make and use the same.

The object of the invention is to provide a flexible spring tube or casing provided with interlocking coils which can also be employed as a simple and easily applied form of armor for hose pipe, such as a pneumatic or railway brake hose, and a pressure or suction hose of all sorts.

The invention also provides a form of tube composed of overlapping and interlocking elements and in which the joints are practically water and dust proof.

The invention comprises the combination of the coils or turns of a spirally wound wire or band enlarged and having preferably rounded edges arranged at different levels, and in which the enlarged edges are connected by a thinner web or member, with an adjoining coil or turn similar in shape and construction and in which the enlarged edges interlock with those of the first named coil or turn. All the interlocking coils or turns may be component parts of one integral coil, or the tube may be composed of a multiple number of coils.

The invention comprises the combination and arrangement of parts to permit of a limited amount of stretching and compression of the coils upon each other, and further consists in the details of construction, hereinafter described and shown in the drawings, and specifically pointed out in the claims.

In the accompanying drawings Figure 1 is a longitudinal section of a hose incased by this tubular armor and bent into a curve showing the action of the component parts of the armor upon each other in expansion and contraction; Fig. 2 is a side elevation of a portion of the interlocking spring tube showing a method of formation and of constructing the interlocking joint; Fig. 3 is an enlarged section of a portion of one side of a straight piece of interlocking spring tube showing a portion thereof completed; Fig. 4 shows the interlocking spring tube

as applied to the exterior and interior of a flexible hose fabric.

In these views A is a band of metal or other suitable substance preferably formed with a body or stem portion 1 having forked extremities 2, 2', integrally connected together. The extreme edges of the body portion and forked extremities are enlarged at 3, 4 and 4', respectively and also preferably smoothly rounded to permit of the easy action of one coil upon another when they are associated together in the completed tube.

In Fig. 3 the manner of interlocking the coils together is shown clearly, the enlarged edge of the body portion of one coil being inclosed between the forks of the next adjacent coil, thus allowing only a predetermined amount of lateral or longitudinal separation of the coils. The enlarged extremities 4, 4', are shown upon different levels, and each extremity 4, 4' is at a different level from the extremity 3, which is inserted between the extremities 4, 4', thus interlocking with the same, and preventing the complete separation of the coils, under working conditions.

A limited movement longitudinally of the hose is permitted by giving a predetermined width to the web forming the body portion 1, and to the webs forming the forks 2 and 2'. This limited movement is essential to permit the flexure of the hose as shown in Fig. 1, the coils being permitted to approach closely to each other on the inner side of the curve and to separate at the outer side of the curve, but the tube as a whole is only slightly extensible as predetermined according to the amount of flexibility required, nor can the coils become entirely separated, since it is not desirable to have the tube stretch unduly or become distorted in such a manner as to be impracticable or decrease the life of the hose or other substance inclosed therein.

The bands with their enlarged ends are magnified in size in the drawings and the actual bands can ordinarily be constructed by drawing them through dies having openings of suitable shape, or by passing through suitably shaped pressure rolls. At C and D, Figs. 2 and 3, a form of F shape is shown which is suitable for this purpose. The edges 3 and 4 lie in their proper positions upon the mandrel, and the extremities 4' can then be formed down over the extremi-

ties 3 upon the adjacent coil, while the coils are being wound upon the mandrel, as shown in dotted lines in Fig. 3. In Fig. 2 E is such a mandrel and the edge 4' is shown at G being formed over the edge 3 upon the body portion.

In Fig. 4 the tube is shown applied as a protective casing both to the interior and exterior of a flexible hose or other suitable material which may thus be used for suction purposes, the hose fabric being protected by the inner flexible metallic tube from the matter passing therethrough, and the outer armor shielding the exterior of the hose from injury. This inner flexible tube also serves to prevent collapse of the intermediate fabric when in service for suction purposes.

I do not confine myself to the use of this flexible interlocking spring tube for armor purposes alone since by the introduction of a suitable elastic and adhesive substance shown at H in Fig. 3, among the interlocking coils A thereof, the tube might constitute a complete tube or hose in itself without lining or covering of any sort. A chamber is formed between the forks in each coil in which the said elastic substance is inclosed. This material can be introduced into the aforesaid chamber while the coils are being constructed upon the mandrel.

The above described coils being made of spring material will always resume their original positions when the tube is elongated or flexed, and hence no cramping or binding of the parts on themselves will occur under ordinary conditions.

Having thus described the invention what I claim as new and desire to secure by Letters Patent is:

1. In a flexible armor, a coiled band having a webbed body portion with an en-

larged single edge, and an integral webbed fork, extending from the opposite edge thereof, said fork provided with enlarged edges, the enlarged edges of the fork in one spiral coil of said band inclosing between them the enlarged edge of the webbed body portion of the adjacent coil.

2. In a flexible metal armor, a coiled band comprising a webbed body portion and forked extremities, and enlarged edges for said webbed body and forked extremities, the said forked extremities inclosing the body portion of the adjacent coil between them, said enlarged edges of said forked portions of one coil adapted to engage and inclose the enlarged edge of the body portion of the adjacent coil.

3. In a flexible, interlocking spring tube, a series of interlocking coils, each coil provided with one enlarged edge, and with one forked edge having enlarged extremities, the enlarged edges of the fork on the edge of one coil inclosing the enlarged edge of the next adjacent coil, the said fork forming a chamber and an elastic substance inclosed in said chamber.

4. In a flexible spring tube, a coiled band having a stem edge and forked edges, and composed of thin metal, said edges enlarged at their extremities, the enlarged forked edges of each spiral coil inclosing the enlarged stem edge of the adjacent coil and forming an inclosure, and an elastic substance in said inclosure in which said stem edge is embedded.

In testimony whereof, I hereunto set my hand this eighth day of May 1913.

LAWRENCE A. SUBERS.
